JOHN D. CONTI, OF PHILADELPHIA, PENNSYLVANIA.

PACKAGE-FILLING MACHINE.

Application filed November 17, 1926. Serial No. 148,790.

My invention relates to packaging machinery and more particularly to a machine for filling paper lined cartons with crackers, biscuits or small cakes.

5 Under the usual method of procedure, crackers come from the oven in large sheets and are broken apart and stacked by hand. Small cakes are not usually baked in sheets but come from the ovens in large batches of 10 individual cakes, after which they go to a stacking machine which piles them in stacks ready for the packers to place them by hand in cartons; the cartons having previously been made, formed and lined with waxed 15 paper by machinery.

The principal object of my invention is to provide a machine which will receive the stacked crackers, biscuits or cakes and place them automatically into cartons.

20 Another object of my invention is to so construct the machine that the requisite number of cakes or crackers will be automatically placed in each carton.

Another object of my invention is to provide a machine in which empty cartons are automatically brought into position to be filled and the filled cartons removed.

These objects, and other advantageous ends which will be described hereinafter, I 30 attain in the following manner, reference being had to the accompanying drawings in which

Figure 1 is a side elevation of an embodiment of my invention, and

35 Figure 2 a rear view of the machine shown in Figure 1.

Figure 3 is a view, taken on line 3—3 of Figure 2, showing the parts of the machine in position to receive a charge of material, 40 and

Figure 4 a view similar to Figure 3 but showing the positions of the parts of the machine when the charge of material has been deposited in a carton.

45 Figure 5 is a view taken on line 5—5 of Figure 2.

Figure 6 is a view taken on line 6—6 of Figure 1,

Figure 7 a top plan view, and

Figure 8 a fragmentary front view. 50

Figure 9 is a fragmentary view, showing the measuring unit as it appears from the far side of the machine,

Figure 10 a view taken on line 10—10 of Figure 9; and 55

Figure 11 a view taken on line 11—11 of Figure 9.

Figure 12 is a fragmentary sectional view taken on line 12—12 of Figure 9, certain parts having been omitted for the sake of 60 simplicity.

Figure 13 is a sectional view, taken on the same section line as Figure 12 but showing the measuring unit in lowered position with its bottom open and the paper guides extended, and 65

Figure 14 a perspective view of the rear paper guide.

Referring more particularly to the drawings, the frame of the machine consists of a 70 pair of rear posts 15 and 15^a and a pair of front posts 16 mounted on a suitable base 17, a pair of longitudinal top pieces 18, a pair of transverse top pieces 19, and a center top piece 20. It is understood, of course, 75 that the base 17 would ordinarily be the floor of the bakery in which the machine is installed.

A trough-shaped conveyor section 21 is mounted on base 17 by means of brackets 80 21^a and connected at one end to a conveyor trough 22, through which empty cartons are fed to the machine, and at its other end to a conveyor trough 23, through which the filled cartons are removed from the machine. The 85 cartons are carried through conveyor sections 21 and conveyor troughs 22 and 23 on an endless belt 24 which rides on the bottom of these members and is actuated in the manner customary in belt conveyors. 90

The cartons, which are represented as a whole by the numeral 25, are of the well

known type consisting of a cardboard outer part 26 folded to form a cover 27 and which are lined with waxed paper 28. In Figures 3 and 4, the cartons are shown in full with the exception of one in Figure 4 which is shown in section and as it would appear at the moment of receiving its charge of crackers.

As the function of the machine consists of several distinct operations, which must be timed with one another, each will be described separately.

The belt 24 runs continuously and tends to move the cartons through the machine in a regular flow but this flow is interrupted and made intermittent by a locating mechanism which will now be described. Referring more particularly to Figures 1, 2 and 6, a bracket 29 is mounted on the side of conveyor section 21 and has an arm 30 rockably mounted in its outer end. Spacers 31 and 31^a are pivotally mounted in each end of arm 30 and extend through suitable slots in the side of section 21. A pair of links 32 has one end pivoted to one end of arm 30 and its other end pivoted to the forward end of a lever 33 which in turn is pivoted at 34 in a bracket bearing 35 mounted on post 15. A lever 36 is pivoted approximately midway of its length to a bearing 37 mounted on post 15 and has a bifurcated lower end which straddles a screw 38 inserted in the end of lever 33. A pin 39 is slidably mounted in a hole in post 15 in such a position that one end will abut the upper end of lever 36 and its other end abut a cam face 40 secured to the back of a mutilated gear 41 fixed on the main drive shaft 42.

As gear 41 rotates, cam face 40 will make contact with pin 39 at certain intervals, as shown in Figures 2 and 5, and move the upper end of lever 36 away from post 15 to which it is pivoted, thus moving its lower end in the opposite direction. As the lower end of lever 36 is attached to the end of lever 33, this movement will be imparted to link 32 and arm 30 and cause spacer 31 to partially enter the interior of member 21, as plainly shown in Figure 6, thus stopping the movement of empty cartons through the conveyor but permitting the filled carton to travel away from the machine.

I have shown the empty cartons being delivered through the rear of the machine and the filled cartons from the front of the machine but it will be understood that this direction may be readily reversed by reversing the movement of belt 24 and the timing of lever 36.

The retarding of the empty cartons is plainly shown in Figure 3, it being understood that the conveyor belt 24 continues to move and the bottom of the cartons slide upon its surface in the manner customary in such conveyors. After gear 41 has made a

partial rotation, the cam face 40 will move out of contact with the pin 39 and the upper end of lever 36 will be drawn toward post 15 by the action of a spring 43 suitably connected between the lever and the post, thus reversing the movement of lever 33, link 32 and arm 30 which causes spacer 31 to be withdrawn from the interior of the member 21 and the spacer 31^a to enter it. As belt 24 is moving continuously, an empty carton is carried forwardly from its position back of spacer 31 until it abuts spacer 31^a, at which time it is in position for filling as shown in Figure 4, in which the carton is shown in cross section with its contents in place. It is understood, of course, that the movement of the spacers, and consequently the movement of the cartons, is co-ordinated with the other movements of the machine.

A trough-shaped conveyor end 44 is secured to front posts 16 and has a roller 45 suitably mounted therein over which an endless belt 46 travels. A conveyor trough, leading to the source of supply, is connected to conveyor end 44 and the belt 46 moves therethrough; its upper half being supported by the bottom of the conveyor trough. As this conveyor is of the type normally employed in moving material from place to place, it forms no part of my invention and will not be further described. The material to be packed is placed edgewise on the conveyor belt, either by hand or mechanically, and is thus conveyed to the machine. In order to maintain the cakes or biscuits on edge, the conveyor trough must be first filled by hand with the front end of the row of biscuits or cakes held upright by the machine, as shown in Figures 3 and 4, and the material in the rear of the row held upright by the stacking machine or by elevating the rear end of the conveyor.

At the beginning of the operation, the cake or biscuit in the front of the row of material in the conveyor is supported in an upright position by a plunger head 47 (see Figure 3) which is attached to a measuring plunger 48, the rear end of which is mounted in a guide bearing 49 on a support 50 attached to the rear posts 15. The forward portion of plunger 48 is supported and guided by an aperture in a plate 51 which also forms the rear end of the measuring compartment.

Movement is imparted from main shaft 42 to plunger 48 through a gear 52 which meshes with mutilated gear 41 and is secured to a shaft 53 mounted in suitable bearings on the rear posts. An eccentric 54 is secured on shaft 53 and is provided with an eccentric rod 55 threaded into the eccentric strap 56 and held in adjusted positions by a jam nut. A lever 57 is pivoted to a brace 58 on the rear posts and has its upper end pivotally connected to the outer end of eccentric rod 55 and its lower end connected to a link 59;

- both ends of the lever being bifurcated to facilitate connection to the link and eccentric rod. A member 60 is adjustably secured on the central portion of the measuring plunger 48 with its upper end pivotally connected to the link 59. It is evident that as shaft 53 rotates, the eccentric 54 will be rotated with it and move plunger head 47 from the position shown in Figure 3 to the position shown in Figure 4. As belt 46 is moving continuously, it is evident that the material will follow plunger head 47 to its rearmost position, thus filling the measuring compartment of the machine.
15. A shaft 61 is mounted in suitable bearings on rear posts 15 and is rotated by means of a gear 62 which is on one of its ends and meshes with mutilated gear 41. A cam 63 is mounted near the center of shaft 61 and a disk 64, having a crank pin 65 set therein is mounted on its other end. A rock shaft 66 is suitably mounted on rear posts 15 and has a grooved crank 67 engaging crank pin 65. A lever 68, bifurcated to clear cam 63, is rigidly mounted near the center of rock shaft 66 and has its front end bifurcated vertically, to straddle a support rod 69 and a filling plunger 70, and bifurcated horizontally to straddle a pin 71 which extends 30 through the filling plunger. A filling plunger head 72 is suitably secured to the bottom end of filling plunger 70 and is adapted to make contact with the tops of the material in the measuring compartment and 35 force it into the waiting carton, as will be later described. The lower end of support rod 69 is provided with a pair of straps which connect to each side plate of a measuring unit 73.
40. Rockably mounted on center top piece 20 is a lever 74, the rear end of which is bifurcated to accomodate a roller 75 adapted to contact with the cam 63. The front end of lever 74 is bifurcated vertically to straddle 45 rod 69 and filling plunger 70, and bifurcated horizontally to straddle a pin 76 mounted through rod 69. Cross braces 77 extend between front posts 16 and are provided with guides 78 and 78^a through which rod 69 and 50 filling plunger 70 slide.
- As shaft 61 rotates, cam 63 will engage roller 75, actuate lever 74 and rod 69, and thus force measuring compartment 73 downwardly. Simultaneously with the rotation 55 of cam 63, disk 64 will rotate and actuate rock shaft 66 through the engagement of crank pin 65 and crank 67, thus moving the outer end of lever 68 downwardly which forces the filling plunger 70 to its lowermost 60 position.
- As plunger head 72 moves downwardly, forward movement of the material in the feeding conveyor is prevented by an upstanding portion 79 on the plunger head.
65. As the movement of the outer end of lever 68 is much greater than the movement of the outer end of lever 74, plunger head 72 will move much farther than will the measuring unit. In other words, measuring unit 73 and plunger head 72 will move downwardly 70 to a point adjacent the top of the carton to be filled, where the unit will remain stationary while the filling head 72 moves downwardly through the measuring compartment of the unit to a point approximately level 75 with the top of the carton.
- The upstanding portion 79 of the plunger head is provided with a shouldered slot 80 (Fig. 8) in which a slide 81 is slidably mounted by means of a slide guard 82 rigidly 80 secured to the rear side of its upper end. A trigger 83 is pivotally connected to the rear side of slide guard 82 and is yieldingly held in its upper position by means of a tension spring 84 connected to its upper end and to 85 guide 78^a. Trigger 83 is provided on its rear edge with a pair of notches forming shoulders 85 and 85^a which are adapted to engage a shoulder 86 formed on guide 78. When plunger head 72 is in its uppermost 90 position shoulder 85^a will contact with shoulder 86, as shown in Figure 3, thus bringing the lower end of slide 81 approximately even with the lower end of the upstanding portion 79 of the plunger head. 95 As the plunger head moves downwardly, slide 81 will come in contact with the top of the slot 80 and be carried downwardly with it, against the action of spring 84, until its lowermost position is reached when shoulder 85 on trigger 83 will come in contact with shoulder 86 and hold the trigger in this position until the plunger head reaches its uppermost position, as shown in Figures 100 4 and 8. It is evident that slide 81 replaces 105 upstanding portion 79 in holding the material in the conveyor against forward movement, initial plunger 47 having moved forward.
- A trip plunger 87, having a roller 88 110 mounted in its bifurcated forward end, is slidably mounted through guide 78 and held in its rearmost position by a compression spring 89 encircling the trip plunger with its ends abutting the guide 78 and a collar 115 90 fixed to the trip plunger. The rear end of the trip plunger is adjustably threaded into a head 91 which is provided with a slot 92 adapted to engage a pin 93 secured to the lever 57. Due to the slot 92 and to 120 the shorter leverage on lever 57, it is evident that the forward movement of the trip plunger 87 will start at a later time and be at a much slower rate than that of the plunger 48, but adjustment is so made that 125 the instant the plunger head arrives at its forward position, the roller 88 on the trip plunger will make contact with an extension 94 on trigger 83 and force same outwardly so as to allow spring 84 to return 130.

the trigger 83 to its uppermost position, thus bringing the material in contact with the plunger head 47 and completing a cycle of operation.

5 Referring now more particularly to Figures 9 to 14, the measuring unit 73 has a side plate 95 on the right hand side and a side plate 95^a on the left hand side which are attached to the rod 69 by means of 10 straps 96. The ends of these plates are slidably mounted in suitable grooves formed in plate 51 and in the ends of the side walls of conveyor end 44. A paper guide 97 is hinged to side plate 95 and is actuated by means 15 of a bent rod 98, one end of which is secured to the hinged part of guide 97 and its other end slidably mounted in a cam slot 99 in plate 51. The guide 97 normally extends inwardly and downwardly from side plate 95 20 so that, as the measuring unit is lowered, the lower edge of this guide may be inserted inside the carton and, as the unit approaches the lowermost point of its movement, rod 98 causes guide 97 to swing outwardly and 25 engage one side of the wax paper lining, thus clearing this side of the carton in preparation for receiving its charge of material.

A bottom piece 100 is hinged to the side plate 95^a and normally lies in a horizontal 30 position to form a continuation of the bottom of the delivery conveyor and remains in this position until the measuring unit has nearly reached the lowermost point of travel when it swings downwardly and outwardly 35 and allows the material contained in the measuring unit to be deposited into the carton below. In its outward movement the bottom piece 100 engages the paper lining on its side of the carton and forces same 40 outwardly to clear this side of the carton. A pinion 101 is rigidly secured to a rod around which portions of side plates 95^a and bottom piece 100 are bent to form a hinge; the rod being loosely held in the bent portions 45 of plate 95^a and rigidly held by the portions of bottom piece 100. Pinion 101 engages a rack 102, formed on a piece 103 which is provided with a slot 104. A shouldered piece 105 is mounted in and over- 50 laps the sides of slot 104 and is rigidly secured to side piece 95^a. A stop 106 is adjustably mounted on the edge of end plate 51, by means of a clamping plate 107, and is adapted to engage a shouldered extension 55 108 on the upper end of piece 103 to prevent further downward movement. A coiled spring 109 has one end secured to shouldered extension 108 and its lower end secured to side plate 95^a, thus tending to hold extension 108 against the top of shouldered piece 105. As the measuring unit moves 60 downwardly, extension 108 will make contact with stop 106, thus preventing this piece from further downward movement and holding rack 102 stationary. As the unit

continues on its downward movement, pinion 101 is caused to rotate by rack 102 and bottom piece 100 is swung on its hinge.

The inner end of conveyor section 44 is provided with a downwardly extending 70 flange 110 on the inner side of which a friction member 111 is yieldably mounted by means of suitable bolts or screws encircled by coiled springs 112, the ends of which abut the adjacent faces of flange 110 and friction member 111 respectively, holding the latter approximately flush with the inner end of conveyor section 44. Hinge parts 113 and 113^a are rigidly secured to the front end of plates 95 and 95^a respectively. 75 A front paper guide 114 is mounted between hinge parts 113 and 113^a by means of a short pin passing through hinge part 113^a and by a bent rod 115 having one end extending through hinge part 113 and its other 80 end engaged in a cam slot 116 formed in a plate secured to the inner end of conveyor section 44. Front guide 114 is provided with a slot slightly larger than friction member 111 over which the front guide is 85 adapted to swing. In its normal position, the front guide hangs nearly vertically and in the same plane with the friction member 111. As the measuring unit approaches the end of its downward movement, bent rod 90 115 will be actuated by cam slot 116 in such a manner as to cause front guide 114 to swing forwardly and engage the paper lining at the front end of the carton.

A division plate 117 is mounted between 100 side plates 95 and 95^a near their rear ends and is bifurcated on its center line to provide a passage for measuring plunger 48. Lugs 118 extend forwardly from the lower corners of division plate 117 and have a rear 105 paper guide 119 journaled between them in such a manner that the upper front edge of the guide lies in approximately the same vertical plane as the face of plunger head 47 when same is in its rearmost position. A 110 bifurcated extension 120 is formed on the top of rear guide plate 119 and extends rearwardly at approximately right angles to the body of the guide. A pair of coiled springs 121 have their upper ends secured near the 115 upper edge of rear plate 51 and yieldingly support a stop 122 which is reduced along its central portion so that it may be straddled by the bifurcated extension 120 on rear guide 119 which is adapted to slide freely on 120 either side of the reduced portion and to make positive contact with the bottom portion of the stop. A retaining strip 123, of the same width as the reduced portion of stop 122 is superimposed on the stop and 125 held in position by counter-sunk head screws which extend through a vertical slot 124 and are threaded into rear plate 51. As measuring unit 73 approaches its lowermost point of travel, the lower end of stop 122

will be engaged by extension 120 and yieldingly hold same against further downward movement which will cause rear guide plate 119 to swing rearwardly and engage the paper lining to clear this end of the carton for the placing of the material therein. As unit 73 is adapted to move slightly farther, stop 122 will be carried with it due to the yielding of springs 121.

10 The different movements of the machine are timed by means of cam 63, eccentric 54, disk 64 and cam face 40, the movements of which are intermittent due to the fact that gear 41 is a mutilated gear which alternately meshes with gears 52 and 62. The intermittent meshing of these gears is controlled by plates 125, 126 and 127 which form the well known Geneva movement for control of mutilated gearing. Plate 125 is 20 rigidly secured to gear 41 and has one semi-circular portion, the radius of which is equal to the pitch radius of gear 41, and a smaller semi-circular portion, which is of such size as to clear the edges of plates 126 and 127. Plates 126 and 127 are rigidly secured to gears 52 and 62 respectively and are circular in shape with the exception of a cut-out portion in each which has a curved edge conforming to, and adapted to contact 30 with, the periphery of the larger semi-circular portion of plate 125. These gears and plates are plainly shown in Figures 1 and 5 and, as this movement is well known, it will not be further described.

35 The machine operates as follows: Measuring plunger 48 is placed in its rearmost position with slide 81 held in its lower position by trigger 83, as shown in Figure 4, and the member 60 loosened so that the measuring plunger may be moved forwardly until the 40 distance between the face of the measuring plunger head 47 and the rear face of slide 81 is slightly greater than the total length of the stack of cakes or crackers which it 45 is desired to place in each carton. Member 60 is then rigidly re-secured to the measuring plunger. The material to be packed in the cartons is properly stacked in the material conveyor and a supply of paper lined cartons placed in the carton conveyor; 50 it being assumed that the supplies of material and cartons will be maintained.

55 Power is then applied which will cause the movement of belts 24 and 46 in the proper directions and the rotation of main shaft 42 in a clockwise direction. This will cause gear 41 to mesh with gear 52 and rotate shaft 53, and consequently eccentric 54, in an anti-clockwise direction and move eccentric rod 55 rearwardly. This movement 60 will cause measuring plunger 48 and trip plunger 87 to move forwardly to the positions shown in Figure 3. As the face of plunger head 47 comes in close proximity to slide 81, which is holding the material

against forward movement, roller 88 on the trip plunger 87 makes contact with the extension on trigger 83 and releases the trigger, which allows slide 81 to fly upwardly 70 in response to the action of the spring 84. The face of the plunger head will then support the forward end of the stack of material in the conveyor.

At the same time that plunger 48 starts forward, cam face 40 engages pin 39 and 75 moves the upper end of lever 36 outwardly, which causes spacer 31 to enter the interior of conveyor section 21, as previously explained, retard the forward movement of the cartons and allow the carton directly under 80 the measuring unit to be carried away.

Continued rotation of main shaft 42 causes continued rotation of the eccentric 54 and the return of plunger 48 to its original position, at which time pin 39 will leave cam face 40 and the positions of spacers 31 and 31^a will be reversed due to the action of spring 43, as previously explained; that is, spacer 31 will be withdrawn from the interior of section 21 and spacer 31^a extended 85 into it so that an empty carton may be positioned directly under the filling mechanism. At this point, gear 41 will disengage gear 52 and engage gear 62 attached to shaft 61, which will be rotated in an anti-clockwise 90 direction, together with the cam 63 and disk 64 mounted thereon. Cam 63 and lever 74 will be in the positions shown in Figure 3 while eccentric 54 and lever 57 will be in the positions shown in Figure 4. Rotation 100 of shaft 61 will cause the faces of cam 63 to elevate roller 75, mounted in lever 74, and force rod 69 and measuring unit 73 downwardly, as previously explained. At the same time, crank pin 65 on disk 64 will 105 actuate grooved crank 67, rock shaft 66, and lever 68, thus forcing filling plunger 70 downwardly.

As the measuring unit and filling plunger move downwardly, the unit 73 will approach sufficiently near the carton for the paper guides to engage the edges of the lining and clear the opening in the carton, at which time bottom 100 flies open and downward movement ceases, due to roller 75 having reached 115 the highest point of the cam 63. Shaft 61 continues to rotate until crank pin 65 has moved a sufficient distance to cause filling plunger head 72 to travel to a point adjacent the lower edges of the paper guides and of bottom piece 100. Continued rotation of shaft 61 reverses the movement just described and returns the parts to their starting positions.

While I have described my invention as taking a particular form, it will be understood that the various parts may be changed without departing from the spirit thereof, and hence I do not limit myself to the precise construction set forth, but consider that I am 125 130

at liberty to make such changes and alterations as fairly come within the scope of the appended claims.

Having thus described my invention, what I claim as new and desire to secure by Letters Patent is:—

1. A machine for packing cakes and biscuits into cartons including a conveyor for supplying material to the machine, a conveyor for carrying empty cartons to and filled cartons from the machine, a measuring unit adapted to receive a predetermined quantity of material, means for stopping an empty carton in position to be filled, means for intermittently stopping the flow of material to the measuring unit, means controlled by a driving member for lowering said unit toward an empty carton, and a filling plunger under the control of said member for guiding said material through the carton.
2. A machine for packing cakes and biscuits into cartons, including a conveyor for supplying material to the machine, a conveyor for carrying empty cartons to and filled cartons from the machine, a measuring unit adapted to receive a predetermined quantity of material, means for stopping an empty carton in position to be filled, means for intermittently stopping the flow of material to the measuring unit, means for lowering the measuring unit toward an empty carton, means for lowering the measuring unit, means in association with said unit and controlled by its downward movement for entering the carton and arranging paper lining therein, and a filling plunger adapted to retain the material in said unit in alignment and guide it through the unit into the carton.
3. A machine for packing cakes and biscuits into cartons including a conveyor for supplying material to the machine, a conveyor for carrying empty paper lined cartons to and filled cartons from the machine, a measuring unit adapted to receive a predetermined quantity of material, means for stopping an empty carton in position to be filled, means for intermittently stopping the flow of material to the measuring unit, means operative responsive to the lowering of the measuring unit for spreading the outer edges of the paper lining of the carton, means adapted to pass through said unit for transferring the material from the measuring unit to the carton to be filled, and means to actuate the conveyors.
4. A machine for packing cakes and biscuits into cartons including a conveyor for supplying material to the machine, a conveyor for carrying empty cartons to and filled cartons from the machine, a measuring unit adapted to receive a predetermined quantity of material, means for stopping an empty carton in position to be filled, means for intermittently stopping the flow of material to the measuring unit, means controlled by a driving member for lowering said unit toward an empty carton, and a filling plunger under the control of said member for guiding said material through the carton.

5. A machine for packing cakes and biscuits into cartons including a conveyor for supplying material to the machine, a conveyor for carrying empty paper lined cartons to and filled cartons from the machine, a measuring unit adapted to receive a predetermined quantity of material, means for stopping an empty carton in position to be filled, means for frictionally holding said material against too rapid a downward movement, and means to actuate the conveyors.

6. A machine for packing cakes and biscuits into cartons including a conveyor for supplying material to the machine, a conveyor for carrying empty paper lined cartons to and filled cartons from the machine, a measuring unit adapted to receive a predetermined quantity of material, means for stopping an empty carton in position to be filled, means for intermittently stopping the flow of material to the measuring unit, means controlled by the measuring unit for spreading the outer edges of the paper lining of the carton, means for lowering the measuring unit toward the carton to be filled, means for lowering the material from the measuring unit into the carton to be filled, means for frictionally holding said material against too rapid a downward movement, and means to actuate the conveyors.

7. In a machine having means for receiving, measuring and packing cakes and biscuits into paper lined cartons, means for stopping a carton in position to be filled including a trough shaped conveyor having a belt running therein, a bearing on the conveyor, an arm rockably mounted on the bearing, a spacer pivoted to each end of the arm and adapted to extend through slots in the side of the conveyor, and means to actuate the arm whereby the spacers will alternately extend into and be withdrawn from the interior of the conveyor.

8. In a machine having a frame and means for receiving, measuring and packing cakes and biscuits into paper lined cartons, means for stopping a carton in position to be filled including a trough shaped conveyor having a belt running therein, a

bearing on the conveyor, an arm rockably mounted on the bearing, a spacer pivoted to each end of the arm and adapted to extend through slots in the side of the conveyor, a link pivoted to the arm, a lever pivoted on the frame and having its forward end connected to the link, a second lever pivoted on the frame and having its lower end connected to the rear end of the first mentioned lever, a gear rotatable on the frame, a cam face on the gear, a pin abutting the cam face and the upper end of the second lever, and means to rotate the gear whereby the spacers will alternately extend into and be withdrawn from the interior of the conveyor.

9. In a machine having a frame and means for receiving, measuring and packing cakes and biscuits into paper lined cartons, means for intermittently stopping the flow of material to the machine including a plunger, an extension on the plunger, a slide on the extension, a trigger connected to the slide, a spring connecting the trigger to the frame, means to actuate the plunger whereby the slide is carried downwardly, means on the trigger for holding the slide in its lower position, and means mechanically connected to the measuring means for tripping the trigger, whereby the slide will be returned to its upper position by the action of the spring.

10. In a machine having a frame and means for receiving, measuring and packing cakes and biscuits into paper lined cartons, means for intermittently stopping the flow of material to the machine including a plunger, a slotted extension on the plunger, a slide in the slot on the extension, a slide-guard holding the slide in the slot, a trigger pivoted to the slide-guard, a spring connecting the trigger to the frame, means to actuate the plunger whereby the slide is carried downwardly, means on the trigger for holding the slide in its lower position, and means mechanically connected to the measuring means for tripping the trigger, whereby the slide will be returned to its upper position by the action of the spring.

11. In a machine having a frame and means for receiving, measuring and packing cakes and biscuits into paper lined cartons, means for intermittently stopping the flow of material to the machine including a plunger, an extension on the plunger, a slide on the extension, a trigger connected to the slide, a spring connecting the trigger to the frame, means to actuate the plunger whereby the slide is carried downwardly, means on the trigger for holding the slide in its lower position, a trip plunger mechanically connected to the measuring means for tripping the trigger, whereby the slide will be returned to its upper position by the action of the spring, means for holding the trip plunger out of tripping position, and

means for adjusting its forward movement.

12. In a machine having means for receiving and packing cakes and biscuits into paper lined cartons; a measuring unit including a pair of side plates, a bottom plate hinged to one of the side plates, and a plunger between the side plates; means to intermittently move the plunger, and means to intermittently swing the bottom plate between open and closed positions.

13. In a machine having a frame, means for packing cakes and biscuits into paper lined cartons, and a conveyor for supplying material to be packed; a brace on the frame, a plate on the brace, a pair of side plates mounted between the plate and the end of the conveyor, a bottom plate hinged to one of the side plates, means to intermittently swing the bottom plate between open and closed positions, a plunger slideable on the brace and extending between the side plates, and means to actuate the plunger.

14. In a machine having a frame, means for packing cakes and biscuits into paper lined cartons, and a conveyor for supplying material to be packed; a brace on the frame, a plate on the brace, a pair of side plates mounted between the plate and the end of the conveyor, a bottom plate hinged to one of the side plates, means to intermittently swing the bottom plate between open and closed positions, a bearing in the plate, a bearing on the brace, a plunger slideable in the bearings and extending between the side plates, a lever having one end mechanically connected to the plunger, an eccentric mechanically connected to the other end of the lever, and means to actuate the eccentric.

15. In a machine having a frame, means for packing cakes and biscuits into paper lined cartons, and a conveyor for supplying material to be packed; a brace on the frame, a plate on the brace, a pair of side plates having their ends mounted in vertical grooves in the plate and in the end of the conveyor, a support secured to the side plates for supporting them in the grooves, a bottom plate hinged to one of the side plates, means to intermittently swing the bottom plate between open and closed positions, a plunger slideable on the brace and extending between the side plates, and means to actuate the plunger.

16. A machine having a frame, a conveyor for delivering material to the machine and means for measuring and packing cakes and biscuits into paper lined cartons including an end plate carried by the frame, a pair of side plates having their ends mounted in vertical grooves in the end plate and in the end of the conveyor, means for intermittently stopping the flow of material into the space between the side plates, a sup-

port secured to the side plates, means connected to the support for lowering and raising the side plates in the grooves, a bottom plate hinged to one of the side plates, means to swing the bottom plate into open position as said plates approach their lowermost point of travel, and means to actuate the machine.

17. A machine having a frame, a conveyor for delivering material to the machine and means for measuring and packing cakes and biscuits into paper lined cartons including an end plate carried by the frame, a pair of side plates having their ends mounted in vertical grooves in the end plate and in the end of the conveyor, means for intermittently stopping the flow of material into the space between the side plates, a support secured to the side plates, means connected to the support for lowering and raising the side plates in the grooves, hinge loops formed on the lower edge of one of the side plates, a hinge rod rockable in the loops, a bottom piece fixed to the hinge rod, a pinion fixed to the hinge rod, a rack engaging the pinion and adapted to actuate same and cause the bottom piece to swing to its open position as the side plates approach their lowermost point of travel, and means to actuate the machine.

18. A machine having a frame, a conveyor for delivering material to the machine and means for measuring and packing cakes and biscuits into paper lined cartons including an end plate carried by the frame, a pair of side plates having their ends mounted in vertical grooves in the end plate and in the end of the conveyor, means for intermittently stopping the flow of material into the space between the side plates, a support secured to the side plates, means connected to the support for lowering and raising the side plates in the grooves, hinge loops formed on the lower edge of one of the side plates, a hinge rod rockable in the loops, a bottom piece fixed to the hinge rod, a pinion fixed to the hinge rod, an operating piece having a slot, a rack on the operating piece engaging the pinion, a retaining piece disposed over the slot and secured to the side plate, a stop on the end plate, an extension on the operating piece adapted to abut the stop when the side plates are near their lowermost point of travel whereby the rack will be held stationary and cause the pinion to swing the bottom piece to its open position.

19. A machine having a frame, a conveyor for delivering material to the machine and means for measuring and packing cakes and biscuits into paper lined cartons including an end plate carried by the frame, a pair of side plates having their ends mounted in vertical grooves in the end plate and in the end of the conveyor, means for inter-

mittently stopping the flow of material into the space between the side plates, a support secured to the side plates, means connected to the support for lowering and raising the side plates in the grooves, hinge loops formed on the lower edge of one of the side plates, a hinge rod rockable in the loops, a bottom piece fixed to the hinge rod, a pinion fixed to the hinge rod, an operating piece having a slot, a rack on the operating piece engaging the pinion, a retaining piece disposed over the slot and secured to the side plate for holding the operating piece in slideable relation to the side plate, a spring connected to the side plate and to the operating piece for holding same in its lowermost position, a stop adjustably mounted on the end plate, an extension on the operating piece adapted to abut the stop when the side plates are near their lowermost point of travel whereby the rack will be held stationary and cause the pinion to swing the bottom piece to its open position.

20. In a machine for packing cakes and biscuits into paper lined cartons having means for supplying the machine with material to be packed, means to receive and discharge cartons, means for stopping a carton in filling position, and a unit for measuring and placing the material in the cartons; means for clearing the opening of the carton including a bottom piece hinged to one side of the unit, a paper guide hinged to the other side of the unit, and paper guides hinged to each end of the unit; the paper guides and bottom piece being adapted to engage the edges of the paper lining of the carton and move same outwardly to provide free access to the interior of the carton.

21. In a machine for packing cakes and biscuits into paper lined cartons having means for supplying the machine with material to be packed, means to receive and discharge cartons, means for stopping a carton in filling position, a unit for measuring and placing the material in the cartons, and means for lowering and raising the unit; means for clearing the opening of the carton including a bottom piece hinged to one side of the unit, a paper guide hinged to the other side of the unit, and paper guides hinged to each end of the unit; the paper guides and bottom piece being adapted to engage the edges of the paper lining of the carton and move same outwardly to provide free access to the interior of the carton.

22. In a machine for packing cakes and biscuits into paper lined cartons having means for supplying the machine with material to be packed, means to receive and discharge cartons, means for stopping a carton in filling position, a unit for measuring and placing the material in the cartons; means for clearing the opening of the carton including a bottom piece hinged to one side of the

unit, and adapted to open as the unit approaches its lowermost point of travel, a side paper guide hinged to the unit and having a bent rod secured thereto with its other end engaged in a cam slot formed on the machine, a front paper guide hinged to the unit and having a second bent rod secured thereto with its other end engaged in a second cam slot formed on the machine, and a rear paper

guide hinged to the unit, a stop on the machine, an extension on the rear paper guide, and means for raising and lowering the unit

whereby the extension will engage the stop, the bent rods be actuated by the cam slots,

and the paper guides swung outwardly as

the unit approaches the lowermost point

of its travel.

26. In a machine for packing cakes and

biscuits into paper lined cartons, a conveyor

for delivering material to the machine, a

unit for receiving the material, means

to lower the unit, means to transfer the

material from the unit to the carton to be

filled, and means for yieldingly holding the

material against too rapid a downward move-

ment including a bracket on the conveyor,

pins on the bracket, a plate on the pins, and

coiled springs encircling the pins and abut-

ting the bracket and the plate.

27. A package filling machine comprising

a conveyor for supplying material to the

machine, means for carrying empty cartons

to and filled cartons from the machine, a

measuring unit adapted to be filled with said

material, means for stopping a carton to be

filled, means for lowering said measuring

unit, said last means controlling the engage-

ment of paper lining in the carton, a plunger

adapted to move through the unit for pack-

ing said material into the carton.

28. A machine for packing cakes or the

like into cartons having conveying means

for carrying empty cartons to and filled car-

tons from the machine, means for feeding

material to said cartons including a measur-

ing compartment adapted to be intermit-

tently lowered and raised, means for position-

ing a carton to be filled, means for lowering the

measuring unit and actuating a filling plun-

ger to move downwardly through the com-

partment to a point approximately level

with the top of the carton.

29. Means for automatically packing cakes

or the like having a drive gear controlling

the positioning of empty cartons to be filled

and the removal of filled cartons, means con-

trolled by said gear for filling a measuring

compartment, means controlled by said gear

for intermittently lowering and raising said

compartment, means responsive to the lower-

ing of the compartment for opening the com-

partment, and means for packing the mate-

rial into a carton.

30. A machine for packing biscuits or the

like into cartons comprising a conveying

system for feeding and removing cartons

in the machine and for feeding material to

a measuring unit, a pivoted arm having ex-

tensions adapted to position an empty car-

ton to be filled, and cause the removal of a

filled carton, said measuring unit being

adapted by a spring controlled member and

a measuring plunger to be intermittently

filled, and means controlled by the device

operating said pivoted arm for lowering

said unit, causing said unit thereupon to

position paper lining in said carton, said device adapted to cause a filling plunger to pack said material into the carton. said unit being adapted to receive a charge 10 of material, means for lowering the unit toward the carton, and means operative responsive to the lowering movement for automatically swinging open the bottom portion of the unit as it approaches the carton. 15

31. A machine for packing biscuits or the like into cartons including a measuring unit, means for positioning a series of empty cartons to be filled by said unit, a filling means for contacting with material in the unit and guiding the material into the cartons, In testimony whereof I have signed my name to this specification. JOHN D. CONTI.
